UNITED STATES PATENT OFFICE.

LEWIS E. CURTIS, OF CHICAGO, ILLINOIS, ASSIGNOR TO THE TIMEWELL SACK FILLING AND SEWING MACHINE COMPANY, OF SAME PLACE.

FILLED-SACK-SEWING MACHINE.

SPECIFICATION forming part of Letters Patent No. 639,216, dated December 19, 1899.

Application filed March 27, 1899. Serial No. 710,588. (No model.)

To all whom it may concern:

Be it known that I, LEWIS E. CURTIS, a citizen of the United States, residing in Chicago, in the county of Cook and State of Illinois, 5 have invented a new and useful Improvement in Filled-Sack-Sewing Machines, of which the following is a specification.

My invention relates to machines for sewing filled sacks.

10 Filled-sack-sewing machines heretofore in use have employed an opening and closing sack-holder for clamping and holding the mouth edges of the sack closed while being operated upon by the sewing mechanism, said 15 machines being constructed and operating either upon the principle of the Timewell patents, Nos. 476,778, 539,455, 548,029, 562,438, 597,075, 607,809, 607,810, and 607,811, in which the sack-holder has a forward traveling 20 movement past the stitching mechanism and serves to feed or convey the sack-mouth past the needle at the rate the stitching is done, or else operating on the principle of the Becker patents, Nos. 542,549, 608,567, 608,638, 25 and 608,639, in which the sack-holder is stationary and the sewing mechanism is mounted on a movable carriage or slide that travels from one end of the holder to the other at the rate the stitching or sewing is done. In both 30 these types of machines the forward movement or travel of the holder or sewing mechanism, the one in respect to the other, is relied upon to accomplish the feed of the sack-mouth to the needle during the sewing operation and 35 to hold the sack-mouth in position against the thrust of the needle, the sewing mechanism itself not having the customary feed device.

The constructing of a filled-sack-sewing machine with a sack-holder and the necessity for 40 giving either the holder or the sewing mechanism itself a traveling movement to accomplish the feed materially complicates the mechanism of the machine, requires time and labor to insert the sack-mouth in the holder, 45 gives an undesirable rigidity to the fabric of the sack-mouth, especially in withdrawing the needle therefrom, owing to the weight and tension due to the contents of the filled sack, requires nicety of construction and accuracy 50 of adjustment to keep the different parts in proper registry, and renders it impossible to

sew the sack near the upper edge of its mouth, thus preventing the full capacity of the sack being utilized.

The object of my invention is to provide a 55 filled-sack-sewing machine of a simple, efficient, cheap, and durable construction by means of which the difficulties or objections above mentioned may be all overcome and by means of which sacks, and especially small 60 sacks—such as five-pound, ten-pound, or twenty-five-pound sacks—may be very rapidly and cheaply sewed without danger of tearing the fabric of the sack or breaking the needle, as is unavoidably the case in machines 65 where the mouth of the filled sack is rigidly held in a holder having a positive forward movement or travel in respect to the sewing mechanism.

My invention consists in the means I employ to practically accomplish this important object or new result—that is to say, it consists in the combination, with a sewing mechanism, of a sack-conveyer upon which the filled sacks rest and are supported in an upright position and an intermittently-operating feed-dog for the sewing mechanism operating in conjunction with a casing on one side of the sack-mouth and a presser-foot on the opposite side thereof to feed the sack-mouth 80 forward step by step the distance of a stitch at each step in unison with the forward movement of the filled sack as it is carried along by the conveyer—that is to say, the total amount of forward movement of the feed-dog 85 in a given period is equal to the total forward movement of the sack-conveyer in the same period—said feed being preferably a four-motion feed and operating to feed the sack-mouth forward only at the intervals when the needle is withdrawn therefrom, the feed, the sack-conveyer upon which the sacks rest, and the sewing mechanism all co-operating in proper time with each other.

It also consists in the novel construction of 95 parts and devices and in the novel combinations of parts and devices herein shown and described, and specified in the claims.

In the accompanying drawings, forming a part of this specification, Figure 1 is a plan 100 view of a filled-sack-sewing machine embodying my invention. Fig. 2 is a side ele-

vation. Fig. 3 is an enlarged rear elevation. Fig. 4 is a detail plan view, partly in horizontal section, on line 4 4 of Fig. 3. Fig. 5 is a detail bottom view looking from the line 5 5 of Fig. 2. Fig. 6 is a detail view of a clutch device. Figs. 7, 8, and 9 are detail views of the feed mechanism by which the sack-mouth is fed in unison with the needle and with the filled-sack conveyer. Fig. 10 is a detail section on line 10 10 of Fig. 1; Fig. 11, a detail section on line 11 11 of Fig. 4; Fig. 12, a similar view to Fig. 10, showing a slight modification; and Fig. 13 is a detail section on line 13 13 of Fig. 4. Fig. 14 is an enlarged view of the parts shown at Fig. 6.

In the drawings, A represents the frame of the machine.

B is a filled-sack conveyer or carrier, the same consisting, preferably, of an endless belt 20 or apron traveling on horizontal pulleys B' B², so that the sacks resting thereon may be supported in an upright position.

C C are side guides or guards to hold the sacks in an upright position as they are carried forward one after the other by the conveyer. These side guides or guards are preferably sectional, so that they may be attached to the conveyer and move with it instead of being stationary or secured to the frame at 25 each side of the conveyer.

D is the sewing-machine, the same being of any suitable or well-known construction and comprising a needle d and looper d'.

F is an intermittently-operating feed-dog 35 having the customary serrations f on its face to engage the fabric of the sack-mouth. The intermittent feed F is preferably of the well-known four-motion type—that is to say, having a forward reciprocation the length of a 40 stitch to feed the sack-mouth forward, a side movement to withdraw it from the sack-mouth, a backward reciprocation to bring it into position for the next forward movement, and a return side movement to bring 45 it again in contact with the fabric of the sack-mouth. The intermittent feed F is mounted within the casing G, the face-plate g of which has a slot g' for the feed to project through.

H is the presser-foot, the same having a 50 curved end h and being secured to reciprocating stem H', which is forced against the sack-mouth by spring H².

K is a guide or extension of the casing G, the same having a curved outer end and 55 serving to facilitate the insertion of the sack-mouth between the presser-foot on the one side and the casing G and feed F on the other side.

L is a rotating feed-wheel operating, in conjunction with the shoe L', to feed and hold 60 the thread or chain of stitching.

M is a stationary knife or cutter operating, in conjunction with the reciprocating knife or cutter M', to cut the thread or chain of 65 stitching which would otherwise unite the filled sacks after they are sewed.

N N' are rotating feed-wheels which serve

to carry the sack-mouth and the thread or chain of stitching free from the sewing mechanism.

P and P' are two movable arms or levers projecting in the path of the sack-mouth and connected with a clutch mechanism for starting and stopping the sewing mechanism, so that, if desired, the sewing mechanism may 75 be automatically set in motion by the act of inserting the sack-mouth between the presser-foot H and the easing G or its extension K, the arm P serving to move the clutch to set the sewing mechanism in operation and the 80 lever P' to stop the same after the sack has passed the needle and the sewing thereof has been completed. The pivoted arms or levers P and P' are connected together by a pivoted link P², and they are connected by a link P³ 85 to the operating-arm P⁴ of a delicate and easily-operated supplemental clutch Q Q'. A spring P⁵ serves to retract the supplemental clutch-lever Q Q' and hold the pivoted arms P P' in position for engaging the sack-mouth. 90

The clutch Q Q' consists of a disk Q, fast on the shaft q, parallel to the main driving-shaft R² of the sewing mechanism, and a pulley-hub Q', loose on said shaft. The part Q is fixed to the shaft q and carries a friction-band q', which surrounds the hub Q' on the clutch-driving pulley q², the pulley q² being loose upon the shaft q. The ends of the band q are connected together by means of a lever q³, the end of which bears against a projection q⁴ 100 upon the clutch member Q. The band is held from embracing the clutch member Q' by a projection q⁵ upon the strap or band q' engaging the forked lever Q². When the fork of the lever Q² is moved from engagement 105 with the projection q⁵ on the band q', the spring q⁷, together with the resistance of the projection q⁴ against the lever q³ upon the clutch member Q, will tighten the band upon the hub Q', thus locking the two together and 110 driving the shaft a half-rotation, when the stop q⁵ will engage a hook q⁸ upon the other fork of the lever Q², when the band will be released. The lever Q² engages and is operated by the lever P⁴, a very slight force being 115 sufficient to oscillate said lever Q² and operate this supplemental or auxiliary clutch, which is employed to move the main clutch R by a cam Q³ on the shaft q by an arm S on the sliding shaft S', said arm being connected 120 to the main clutch-lever R'.

The main clutch R is splined to the driving-shaft R², located above the table of the sewing mechanism and engages a clutch member R³, which is loose on said shaft and fixed to 125 the driving-pulley R⁴. The driving-pulley R⁴ has a secondary pulley-face r, carrying a belt r', by which the pulley q² is continuously driven.

R⁵ is an idle pulley adjacent to the pulley R⁴.

R⁶ is a friction-brake engaging the rear face of the gear R⁷ on the driving-shaft R² of the sewing mechanism for stopping the sewing

mechanism, said friction-brake being connected to and operated by the sliding shaft S', which is actuated by the cam on the supplemental or auxiliary clutch-shaft, as before 5 described.

The looper d' is preferably a rotating looper and is carried by a shaft d², having a gear d³ meshing with an intermediate gear d⁴, which meshes with a gear d⁵ on the looper-driving 10 shaft T, which is furnished with a bevel-gear T', that meshes with the gear R⁷ on the driving-shaft R² of the sewing mechanism.

The needle d of the sewing mechanism is secured to a reciprocating slide or bar d⁶, which 15 is reciprocated by a pivoted lever d⁷ through a connecting-link d⁸, which is operated by an eccentric T² on the shaft T.

The chain take-up or feed wheel L is rotated by a gear L⁸ on the shaft of said feed-wheel 20 through gears L² L³, gear L³ being on the shaft L⁴, which carries a gear L⁵, meshing with a gear L⁶, that meshes with a gear L⁷ on the looper-driving shaft T.

The feed-wheel N is continuously driven by 25 a gear N² on the shaft of said feed-wheel meshing with the gear N³ on the shaft N⁴, which carries a sprocket-wheel N⁵, connected by a chain or belt N⁶ with a sprocket-wheel N⁷ on the worm-shaft B³, through which motion is 30 communicated to the conveyer B.

The four-motion feed-dog F is reciprocated in the direction of the feed by an eccentric f¹⁰ on the looper-driving shaft T engaging one end of the oscillating lever f', the other 35 end of which is connected to the feed. The feed-dog F is moved or reciprocated sidewise or in and out by a cam f³ on the looper-driving shaft T, which engages a slide f⁴, which has a sliding connection permitting motion at 40 right angles to that of the slide f⁴ with the feed-dog F, said sliding connection allowing the feed to reciprocate in the direction that the sack moves.

The conveyer B is preferably driven continuously instead of intermittently, and I have therefore in the drawings shown its driving mechanism connected with the continuously-rotated driving-pulley R⁴ instead of being connected directly with the sewing-machine driving-shaft R². To thus drive the conveyer B, I provide the pulley R⁴ with a sleeve r', which is furnished with a worm b, engaging a worm-gear b² on the worm-shaft B³, which is provided with a bevel-gear b⁴, 55 meshing with a gear b⁵ on the shaft b⁶, which carries a sprocket-wheel b⁷, carrying a belt or chain b⁸, that engages a pulley or sprocket b⁹ on the conveyer-driving shaft b¹⁰. This mechanism thus reduces the motion of the 60 conveyer, so that it carries the filled sacks forward at the same speed that the intermittently-operated feed-dog F feeds forward the sack-mouth.

The movable knife or cutter M' is preferably operated automatically to sever the thread or chain of stitching that would otherwise unite the adjacent filled sacks as they

are sewed. This can most conveniently be done by connecting the reciprocating knife-slide m with the cam Q³ on the shaft q of the supplemental or auxiliary clutch controlling the stopping and starting of the sewing mechanism. For this purpose the slide m is furnished with a projection or roll m', which fits in the cam. 75

The operation is as follows: The filled sacks or bags are placed in an upright position and closely adjacent to each other on the sack holder or conveyer B, the side guard C serving to prevent the filled sacks from tipping 80 over as they are carried forward by the conveyer to the sewing mechanism. If the sacks are very short in length and are dropped or planted firmly upon the conveyer, the side guards may be unnecessary; but with taller 85 sacks the side guards are desirable to prevent danger of the filled sacks tipping or careening over and spilling their contents. By placing the filled sacks closely together on the conveyer one after another they tend to mutually support each other and are presented 90 to the sewing mechanism in proper order or with only a short interval between contiguous sacks, so that the sewing mechanism only has to be momentarily stopped after each sack is 95 sewed. If desired, however, the sacks may be deposited on the conveyer with a greater or less interval between them. As each sack 100 approaches the sewing mechanism the attendant or operator grasps the sack-mouth at its forward and rear points and inserts the front edge thereof between the presser-foot H and the casing G, the guide or extension K serving to facilitate the insertion of the sack-mouth between the presser-foot on the one 105 side and the casing G and feed dog F on the other side. As the sack-mouth is thus inserted it engages the arm or lever P, and thus 110 operates the supplemental or auxiliary clutch Q Q' and causes the auxiliary clutch-shaft q and its cam Q³ to make a half-revolution, and thus applies the main friction-clutch R R³ and starts the sewing mechanism, thus setting the intermittent feed-dog F in operation and causing the sack-mouth to be thereby fed 115 intermittently to the needle and past the same until the sewing operation is completed. When the sewed sack-mouth passes the second operating trigger or lever P', the supplemental or auxiliary clutch Q Q' is again operated, causing its shaft q and cam Q³ to make 120 another half-revolution, and thus causing said cam Q³ at this second half-turn to operate the friction-brake R⁶, thus stopping the sewing mechanism until another sack-mouth 125 is inserted by the operator or attendant between the presser-foot H and the casing G and feed-dog F, when the operation is repeated. At the second half-revolution of the cam Q³ the movable knife or cutter M' is operated 130 and cuts the thread or chain of stitching, thus separating the sack sewed from the chain and from the succeeding sack. The thread or chain take-up or feed wheel L' being geared

to the looper-driving shaft is operated simultaneously with the sewing mechanism. The chain-feed or take-up L, in conjunction with its coöperating shoe or holder L, serves to hold 5 and feed or take up the chain of stitching and prevent entanglement of the same with the sewing mechanism or needle and looper, while the feed-wheels N N' serve to free or discharge the mouth of the sewed sack from the 10 machine. By shifting the driving-belt from the driving-pulley R⁴ to the idle pulley R⁵ the conveyer B and the whole machine may be stopped and started as desired or required. As the intermittent feed-dog F operates in 15 conjunction with the needle d and feeds the sack-mouth forward only at intervals when the needle is withdrawn from the sack-mouth there is no danger in my machine of the needle tearing the fabric of the sack or of breaking 20 the needle, and as the feed-dog operates in conjunction with a yielding presser-foot and also intermittently relaxes or loosens its grasp upon the sack-mouth there is no danger of any undue strain upon the fabric of the sack- 25 mouth or upon the needle or sewing mechanism on account of the weight of the sack and the movement of the carrier or conveyer upon which it rests and by which it is moved steadily forward. Although the conveyer 30 thus carries the filled sack positively to and past the sewing mechanism, its coöoperative connection with the sewing mechanism is thus such as to enable or cause the sack-mouth to be loosely and freely presented to the sewing mechanism, and thereby entirely preventing 35 and overcoming any undue strain upon the sewing mechanism or upon the fabric of the sack-mouth while being operated upon by the sewing mechanism. My machine is thus 40 caused to operate with ease and perfection in sewing filled sacks.

The side guards C are preferably adjustable to and from each to enable the machine to accommodate sacks of various sizes, they 45 being adjustably secured to the conveyer B by screws C', and the conveyer B is adjustable up and down in respect to the sewing mechanism to accommodate sacks of different 50 lengths or heights. For this purpose the shafts of the conveyer-pulleys are journaled in adjustable supports B⁴.

As illustrated in the modification, Fig. 12, the worm through which motion is communicated to the conveyer B is secured to the 55 sewing-mechanism-driving shaft instead of to the continuously-rotating driving-pulley, which is loose on the shaft. In this construction of my invention, therefore, the conveyer B will be stopped and started simultaneously 60 with the sewing mechanism.

The peripheral speed of the feed-wheels L' and N N' in a given period is equal to the

mean rate of progress of the feed-dog F in the same time, and as the feed-dog acts intermittently its forward movement is at a greater 65 speed than that of the periphery of the feed-wheels L' and N N', and it produces a slack in the article being operated upon between the feed-dog and the feed-wheels, through which the needle passes, and this slack is all 70 taken up by the feed-wheels at the moment the feed-dog again begins its forward movement.

I claim—

1. The machine for sewing filled sacks, consisting of a sewing-machine and a feeding mechanism, the latter comprising a power-driven sack-conveyer upon which the sacks rest in an upright position, and means operating in conjunction with a casing on one 80 side of the sack-mouth and a presser-foot on the opposite side thereof to feed the sack-mouth forward intermittently the distance of a stitch at each step at the mean rate of progress of the filled sack as it is carried by said 85 conveyer, substantially as specified.

2. The machine for sewing filled sacks, consisting of a sewing-machine and a feeding mechanism, the latter comprising a power-driven sack-conveyer upon which the filled 90 sacks rest in an upright position, and means operating in conjunction with a casing on one side of the sack-mouth and a presser-foot on the opposite side thereof to feed the sack-mouth forward intermittently the distance of 95 a stitch at each step, said means for feeding the mouth being a four-motion feed and operating to feed the sack-mouth only at the intervals when the needle is drawn therefrom, substantially as specified.

3. The filled-sack-sewing machine, consisting of a sewing mechanism and a feeding mechanism, the latter comprising a presser-foot and an intermittent feed acting on the sack-mouth, and a power-driven sack-conveyer, said conveyer and said intermittent feed having connecting mechanism operating to convey both the mouth and the body of the sack at the same mean rate of progress, substantially as specified.

4. The machine for sewing the mouth of filled sacks, consisting of a power-driven conveyer carrying the filled sack past the sewing mechanism, sewing mechanism provided with a four-motion feed device acting to feed the mouth at the same rate of progress as that of said conveyer, and means for operating said four-motion feed, said sewing mechanism also embodying a presser-foot and opposing casing, substantially as specified.

LEWIS E. CURTIS.
